DISPENSING MEANS FOR FOUNTAIN
BRUSHES

Herbert W. Appell, Mattapan, Mass.

Application November 7, 1949, Serial No. 125,907

1 Claim. (Cl. 222—341)

1

This invention relates to fountain shaving brushes.

An object of this invention is to provide in a shaving brush, means whereby liquid soap may be discharged into the bristles in measured amounts.

Another object of this invention is to provide a fountain brush for liquid soap which embodies a supply chamber and a delivery chamber with a spring-pressed valve normally closing the communication between the chambers, forward movement of the valve effecting communication between the chambers and simultaneously closing the delivery port of the delivery chamber, the delivery port being opened when the valve is released to assume its normal position.

With the above and other objects in view, my invention consists in the arrangement, combination and details of construction disclosed in the drawing and specification, and then more particularly pointed out in the appended claim.

In the drawing,

Figure 1 is a detail side elevation of a fountain shaving brush constructed according to an embodiment of this invention,

Figure 2 is a longitudinal section taken on the line 2—2 of Figure 1,

Figure 3 is a sectional view taken on the line 3—3 of Figure 2.

Referring to the drawing, the numeral 10 designates generally a cylindrical brush body formed with a head or outer end 11 within which bristles 12 are firmly secured. The head or end 11 is provided with a centrally disposed opening 13 through which soap or the like is adapted to be discharged.

A cylindrical fluid reservoir 14 telescopes within the body 10 and is provided with a forward wall 15 having an opening 16 therethrough. A cap generally designated as 17 is threaded on the inner or rear end of the reservoir 14, being formed with an annular internally threaded flange 18, and a wall 19.

A flared skirt 20 extends from the flange 18 and serves as a base or support for the brush when the latter is not in use. The reservoir 14 has projecting from the forward end thereof a cylindrical chamber 21, formed with a forward wall 22 having an opening 23 axially aligning with the outlet opening 13. The chamber 21 constitutes a measuring chamber within which a quantity of liquid soap is adapted to be discharged, and subsequently discharged from chamber 21 through opening 23 and opening 13 into the bristles 12.

2

A cylindrical valve plug 24 is adapted to normally engage in the opening 16 and is connected with a plunger 25 by means of a relatively small diameter stem 26 which has a diameter substantially smaller than the diameter of opening 16. A spring 27 is interposed between the wall 15 and the forward end of plunger 25 and constantly urges the plunger 25 and the valve member 24 rearwardly to maintain the valve member 24 in closed position with respect to the valve port 16.

A stud 28 projects from the rear end of the plunger 25, loosely engaging through opening 29 formed in the cap wall 19, and a flexible or compressible gasket 30 is disposed on the stud 28, bearing against the rear end of the plunger 25 and adapted to normally bear against the forward or inner side of the wall 19.

In the use and operation of this brush, liquid soap S is discharged into the reservoir 14 by removing the cap 17. At this time the valve member 24 will be in closed position with respect to the delivery opening or port 16. When it is desired to discharge soap into the bristles 12, the stud or operator 28 is pushed inwardly moving the plunger 25 and the valve member 24 forwardly. The forward end of the valve member 24 will at this time be disposed within the delivery opening 23 so as to close this opening, whereas the stem 26 will be positioned within the area of the opening or port 16, thereby permitting the soap in reservoir 14 to flow into the delivery chamber 21. The soap in chamber 21 is discharged into the bristles 12 by holding the device in the position shown in Figures 1 and 2, and releasing the plunger 25. With release of plunger 25, valve member 24 will move upwardly to closed position by action of spring 27 and delivery port 23 will be opened so that the liquid soap in chamber 21 may flow downwardly into the bristles 12, through opening or port 13.

The brush hereinbefore described will provide a means whereby liquid soap may be dispensed to the bristles of a shaving brush or the like in measured quantities.

I do not mean to confine myself to the exact details of construction herein disclosed, but claim all variations falling within the purview of the appended claim.

What I claim is—

A dispensing means for a fountain brush comprising a reservoir having spaced front and rear walls, said front wall being formed with a delivery port, a discharge chamber carried by said reservoir and projecting forwardly of said front wall, said chamber including a wall apposed to and

spaced from the front wall of the reservoir and having a discharge port aligned with said delivery port, a valve plug slidable in said delivery port, a plunger in said reservoir, a stem connecting said valve plug with said plunger, a stud fixed to said plunger and extending slidably through the rear wall of the reservoir, a spring positioned between the plunger and the front wall of the reservoir and constantly urging said valve plug to closed position with respect to said delivery port, said valve plug being at least equal to the length of the discharge chamber and being of substantially the same cross sectional size as the delivery and discharge ports to seal off said ports when positioned therein whereby movement of said plunger and valve plug towards the front wall of the reservoir moves the valve plug into said discharge port to close off said discharge port while simultaneously disposing said valve plug in open position with respect to said delivery port whereby said discharge chamber may be filled from said reservoir; said plunger upon such movement towards the front wall of the reservoir forcing

material in said reservoir through said delivery port.

HERBERT W. APPELL.
